(57) **CLAIM**

The ornamental design for a display panel or screen with animated graphical user interface for physical fitness as shown and described.

DESCRIPTION

FIG. 1 is a front view of a display panel or screen with animated graphical user interface for physical fitness showing a first image of our new design;

FIG. 2 is a front view of a second image thereof;

FIG. 3 is an enlarged view of the area 3 indicated in FIG. 1; and,

FIG. 4 is an enlarged view of the area 4 indicated in FIG. 2. The evenly-spaced broken lines in FIGS. 1 and 2 depict portions of the display panel or screen with animated graphical user interface for physical fitness that form no part of the claimed design. The single dot-dash broken lines in FIGS. 1, 2, 3 and 4 represent the boundary of an enlarged area of the design and form no part of the claimed design. The appearance of an image sequentially transitions to another between FIG. 1 and FIG. 2. The process or period in which an image transitions to another forms no part of the claimed design.
